ROLLER SLIDE FOR RADIAL ARM SHAPERS

Earl T. Pankonin, Chicago, Ill., assignor to Onsrud
Machine Works, Inc., Chicago, Ill.

Application September 23, 1948, Serial No. 50,777

5 Claims. (Cl. 90—13.3)

1

This invention relates to automatic guide rollers for radial arm shapers and particularly to power actuated shiftable guide rollers for causing disengagement of the cutter from the work at predetermined periods during the operation of radial arm shapers.

The main objects of this invention are to provide an improved slidably mounted support for the cutter guide roller of radial arm shapers; to provide an improved power actuated guide roller slide for radial arm shapers; and to provide an improved guide roller construction for radial arm shapers by which the cutter can be automatically disengaged from the work at any time or upon completion of the cutting operation.

A specific embodiment of this invention is shown in the accompanying drawings in which

Figure 1 is a fragmentary perspective view showing the manner in which the invention is applied to a radial arm shaper.

Fig. 2 is a plan view of the improved roller slide construction as taken on line 2—2 of Fig. 3.

Fig. 3 is a sectional elevation of the same, as taken on line 3—3 of Fig. 2, showing the actuating mechanism and the relation of the device to the cutter of a radial arm shaper.

Fig. 4 is a similar view showing the guide roller slide in extended position to disengage the cutter from the work, and

Fig. 5 is an end view of the device showing the manner in which the guide roller slide is mounted on its supporting column.

The improved roller slide is intended particularly for use with radial arm shapers wherein the cutter projects from the end of a pivotally mounted arm, which in turn is automatically actuated to normally swing in a direction so as to cause engagement of the cutter with the work. This type of shaper is well-known in the art and details of the shaper, the arm actuating means and the mounting of the radial arm are therefore not shown, however, as herein shown and described the invention is embodied in a radial arm shaper comprising a horizontal arm 1 having a self contained power unit or motor 2 mounted on its outboard end in a vertical position so that the motor can drive a spindle 3 which in turn carries a cutter 4 arranged to rotate on the vertical axis. A support column 5, for the guide roller slide, is also rigidly mounted on the outboard end of the radial arm parallel with the axis of the motor 2 and the cutter spindle 3; and the column 5 extends downwardly to a point beyond the bottom end of the cutter 4, where the improved slide mechanism and its operating means are mounted.

2

In the form shown the bottom end of the support column 5 is provided with an enlarged foot, or end portion 6, in which a horizontally disposed slide 7 is mounted between inwardly cut V-shaped grooves 8 formed in the bottom surface of the foot as shown in Fig. 5.

The grooves 8 extend transversely across the bottom of the foot 6 toward the axis of the cutter 4; and the slide 7, which is shiftable along the grooves 8, extends a considerable distance beyond each side of the foot as will be hereafter explained. It will be understood that the slide is beveled at its sides to fit the grooves 8 and be retained thereby, and the sliding surfaces thus formed will be lubricated by means of a grease fitting 9, which communicates with one or more channels 10 extending transversely across the slide surfaces and across the grooves 8 as indicated in Fig. 5.

20 Also, as shown in Fig. 5, and in order to facilitate the installation of the slide 7 on the bottom surface of the foot 6, one side of the slide guide is made in the form of a removable bar 11 arranged as an insert in the foot 6 at one side of the slide guideway and having one edge beveled to provide the respective guide channel 8 for the slide. The bar 11 is secured in place on the foot 6 by means of suitable bolts 12 which extend downwardly from the upper surface of the foot 6 through appropriate bores.

As shown in Fig. 3, the slide 7 is arranged to extend a substantially equal distance on each side of the support column 5 and the left hand side of the slide carries a guide roller 13 which is suitably mounted on the upper side of the slide on a vertically disposed stub shaft 14 extending upwardly from the slide and carrying a suitable bearing 15 which provides for free rotation of the guide roller 13.

40 Normally the slide 7 is positioned so that the axis of the guide roller will be substantially concentric with the axis of the cutter 4 and its spindle 3, and to assure accurate positioning of the guide roller with respect to the cutter, in the normal position, a stop block 16 is fixedly mounted on the upper surface of the slide 7 and is provided with a set screw 17 disposed so that its head will engage against the support column 5. The set screw 17 is threaded into the stop block 16 and can thus be adjusted to set the relationship of the roller 13 and the cutter 4 and a jam nut 18, threaded on the set screw 17, is provided to lock the set screw in the desired position.

As shown, the stop block 16 is also arranged to carry a felt pad 19 which engages the periphery of the guide roller 13 to keep it wiped clean of

dust or shavings that might otherwise gather and cause inaccuracy in the shaping operation by coming between the guide roller and the pattern against which it engages.

The automatic actuation of the slide 7, to cause the guide roller 13 to be projected laterally beyond the cutter 4, is obtained by a power means or pneumatic motor comprising an air cylinder 20 horizontally disposed and housed within the body of the support column 5, as indicated in Figs. 2, 3 and 5. The air cylinder is clamped in place in the support column 5 by means of an end plate 21 which is arranged to tightly set over the outboard end of the air cylinder and to be clamped to the support column 5 by means of suitably disposed bolts 22, which extend through holes drilled in the clamp 21 and are threaded into suitably tapped openings on the side of the support column 5. The end plate 21 is also provided with an air connection 23 which communicates through the end plate with the interior of the air cylinder 20 by means of a passage 24.

A piston 25 is disposed within the air cylinder and is suitably mounted on the end of a piston rod 26 which extends outwardly from the air cylinder through a packing gland 27, suitably mounted on the outer side of the end plate 21 by means of bolts 28. The piston rod 26 is connected at its outermost end to the slide 7 by means of a suitable bracket 29 which in turn is rigidly secured on the end of the slide 7 opposite the end on which the guide roller 13 is mounted. The length of the projection of the slide 7 on the opposite side of the column from the location of the cutter and the guide roller, the stroke of the piston 25, and the length of the piston rod 26, are predetermined so that when the piston 25 is at the inner end of the cylinder 24 the slide will be projected outwardly relative to the cutter 4 a distance sufficient to completely disengage the cutter from the work and allow the positioning of a new blank over the pattern. This projected relationship of the slide and the innermost position of the piston 25 are shown in Fig. 4 wherein the pattern, which is engaged by the roller 13, is indicated by the numeral 30 and the work is indicated by the numeral 31.

In the operation of the device the piston 25 is actuated by compressed air introduced through the air connection 23 and controlled by a suitable air valve, not shown, which is arranged to automatically deliver air to the cylinder 20 at a predetermined time in the shaping cycle, and to automatically bleed the air from the cylinder 20 after a new blank has been clamped over the pattern 30. It will be understood that such a control valve may be either automatically or manually operated depending upon the nature of the shaper on which the present invention is used. Such automatic or manually operated control valves are well-known in this art and therefore need not be shown or discussed in detail.

Normally the slide 7 will be in its retracted position such that the guide roller or pattern follower 13 will be substantially aligned with the cutter 4, in which position the cutter will be engaged with the work to be shaped while the roller 13 is engaged with the pattern. When the shaping operation has been completed the piston 25 is actuated to project the slide 7 from the support column 5, in the direction of the cutter, so as to cause the cutter and the radial shaper arm

on which the cutter is mounted to be pushed laterally away from the work, the roller 13 pushing against the periphery of the pattern, which is fixed on the work table, to accomplish this result. When the cutter 4 is disengaged from the work, the finished work is removed and a new blank is placed over the pattern 30 and is clamped in position by means well-known in the art and, therefore, not shown. The control valve is then operated to permit the air to be bled from the cylinder 20 so that the slide 7 can be pushed back to its normal position.

In radial arm shapers, the arm on which the cutter is mounted is normally urged constantly, by suitable means, in a direction so as to move the cutter toward the work, therefore, when the air pressure is released from the cylinder 20, the cutter is automatically brought into engagement with the work and the slide 7 is pushed back or retracted until it is stopped by the stop screw 17 engaging against the foot of the support column 5. At this position the proper depth of cut is had and is maintained by contact of the roller on the periphery of the pattern.

The main advantages of this invention reside in the provision of a power actuated means for disengaging the cutter from the work to allow the removal of the shaped work and the positioning of a new blank on the pattern; and in the provision of such a means that will not only permit accurate positioning of the cutter with respect to the pattern, but which will also provide for adjustment of the retracted position of the slide to vary the cutter and roller alignment in order to compensate for wear on the cutter.

Further advantages of the invention reside in the fact that the construction permits the radial arm supporting the cutter to be constantly urged resiliently in the direction to move the cutter into the work and provides a means for shifting the cutter away from the work, in order that a new blank may be positioned on the pattern, without the necessity of stopping the cutter rotation or releasing the force urging the cutter into the work. And still further advantages are to be found in the simple and sturdy construction of the device and in its fast and accurate operation whereby the operator may without mechanical interference, more readily remove the finished work and place a new blank thereby improving the efficiency of the shaper and the rate of its output.

Although but one specific embodiment of this invention is herein shown and described, it will be understood that numerous details of the construction shown may be altered or omitted without departing from the spirit of the invention as defined by the following claims.

I claim:

1. In a shaper having a movable radial arm, a cutter spindle and cutter on said arm and movable therewith, and a guide roller support column rigidly mounted on said arm in fixed parallel relation with said spindle, a slide mounted on said column and extending transversely of the spindle axis, said slide being disposed axially beyond the end of the cutter, a guide roller mounted on said slide adjacent said cutter, power means on said column for shifting said slide through a continuous stroke of predetermined length laterally across the axis of said cutter and relative thereto, and means to energize said power means.

2. In a shaper having a radial arm swingable about a fixed axis, a cutter spindle and cutter on said arm, and a guide roller support column rigidly mounted on said arm parallel with said spindle and movable therewith, a slide mounted on said column and having one end extending transversely across the spindle axis, said slide being disposed axially beyond the end of the cutter, a guide roller mounted on said one end of said slide adjacent said cutter on an axis parallel therewith, a pneumatic motor mounted on said column and connected to said slide for shifting said slide a predetermined distance transversely across the cutter axis upon actuation of the motor, and means to introduce compressed air to said motor to actuate the same.

3. In a radial arm shaper having a cutter movable laterally toward and away from the work and normally urged toward the work, a guide roller support column mounted parallel with said cutter and movable therewith, a slide mounted transversely on said column and extending therefrom toward the cutter axis, said slide being disposed axially beyond the end of the cutter and movable relative to the cutter axis in the direction of the work, a guide roller mounted on said slide adjacent said cutter and on an axis parallel therewith, an air cylinder mounted on said column, a piston in said air cylinder having a piston rod extending therefrom, means to introduce compressed air to said cylinder to actuate said piston, and means connecting said piston rod and said slide for shifting said slide and guide moving the roller laterally beyond the cutter and in the direction of the work upon each actuation of said piston.

4. In a radial arm shaper having a cutter movable laterally toward and away from the work and normally urged toward the work, a guide roller support column mounted parallel with said cutter and movable therewith, a slide mounted transversely on said column and extending therefrom toward the cutter axis, said slide being disposed axially beyond the end of the cutter, a guide roller mounted on said slide adjacent said cutter and on an axis parallel therewith, said slide and guide roller being movable relative to the cutter in the direction of the work, an air cylinder mounted on said column, a piston in said

air cylinder having a piston rod extending therefrom, means to introduce compressed air to said cylinder to actuate said piston, means connecting said piston rod and said slide arranged to shift said slide and guide roller relative to the cutter in the direction of the work upon actuation of said piston, and an adjustable stop means on said slide arranged to limit the return movement of the slide and position said guide roller in predetermined relation with said cutter.

5. In a radial arm shaper having a cutter movable laterally toward and away from the work and normally urged toward the work, a guide roller support column mounted parallel with said cutter and movable therewith, a movable slide mounted transversely on said column and extending therefrom toward the cutter axis in the direction of the work, said slide being disposed axially beyond the end of the cutter, a guide roller mounted on said slide adjacent said cutter and on an axis parallel therewith, an air cylinder mounted on said column above said slide and with its axis parallel therewith, a piston in said air cylinder having a piston rod extending therefrom, means to introduce compressed air to said cylinder to actuate said piston, a bracket rigidly connecting said piston rod and slide whereby said slide and guide roller will shift relative to the cutter in the direction of the work upon actuation of said piston, and an adjustable stop means arranged to limit the movement of said slide in the opposite direction and position said guide roller in predetermined relation with said cutter.

EARL T. PANKONIN.
